UNITED STATES PATENT OFFICE.

ARTHUR L. BOUCHER, OF NEW YORK, N. Y., ASSIGNOR TO NEW YORK CIGARETTE MACHINE COMPANY, OF NEW YORK, N. Y., A CORPORATION OF NEW YORK.

CIGARETTE-TIPPING MACHINE.

No. 873,014.

Specification of Letters Patent.

Patented Dec. 10, 1907.

Application filed October 15, 1906. Serial No. 338,892.

To all whom it may concern:

Be it known that I, ARTHUR L. BOUCHER, a citizen of the United States, and a resident of the city of New York, borough of Brooklyn, county of Kings, and State of New York, have invented certain new and useful Improvements in Cigarette-Tipping Machines, of which the following is a specification.

My present invention is an improvement on the machine illustrated and claimed in my patent, dated the 18th day of September, 1906, and numbered 831,034; and many of the parts used in this machine are similar to the machine illustrated in that patent.

15 The object of my present machine is to apply a cork tip to a cigarette rod after it has been formed in the cigarette machine and before the rod is cut, so that I thereby secure many advantages over a machine which applies the cork tip to the paper strip before it is made into a cigarette rod.

For the purpose of securing the best results, the tipping machine is placed between the cigarette former and the cutting knives, 25 so that there will be no interference with the working of the cigarette machine proper, since the cigarette rod is not disturbed or distorted by any action of the tipping machine. There are many advantages derived from 30 machines which apply the cork tip to the rod, in preference to the paper before the rod is formed. The particular reasons are, that in securing a cork tip to the paper the adhesive is not perfectly dried before it reaches 35 the former, and when the tip is applied before the paper enters the same, it is very apt to slip upon the paper and interfere with its position upon the finished product. Secondly, the action of the paper in the former 40 is not so liable to be interfered with when the tip is applied after leaving the former. Besides the reasons stated, the machine is more perfect in its application of the tip, and is somewhat simplified in construction.

45 The machine is adapted to apply the tips to the rod, transversely thereof, from a continuous band consisting, preferably, of a piece of cork sufficiently wide to form two tips on two cigarettes, so that the cutting 50 knife will sever the tip thus applied, in the middle, and two cigarettes will thus be formed without any inaccuracy.

The tipping machine proper is adapted to reciprocate back and forth in the direction of the cigarette rod substantially the length of

two cigarettes, so that as the same is following the rod that distance, it is at the same time applying the cork tip for two cigarettes. In this way the tipping machine only travels back and forth one-half as many times as 60 would be necessary if one cigarette only was tipped by each action, which is a material advantage, aside from the matter of accuracy.

In the construction of the machine, I provide the operating parts upon a movable 65 plate, which travels on a bed, and is actuated by a wheel which carries a pin revolving in the arc of a circle; this pin and the parts of the machine are so arranged that the plate carrying the movable parts will be caused to 70 reciprocate on the bed in a longitudinal direction, while the cam block which operates the various other parts, moves in a vertical direction, caused by the action of the pin on the revolving wheel, the cam block being the 75 member with which the pin on the wheel directly engages. By reason of the horizontal movement of the parts on the bed and the vertical movement of the pin in the cam block, the machine is able to respond to the 80 movement of the pin on the wheel.

The machine partially adjusts the cork tip to the rod, preferably underneath the rod, then passes through the curving thimbles which are arranged in alternate positions, so 85 that as the rod enters the first thimble, one of the free ends of the tip is brought down against the rod and pasted thereto. The rod then passes on and enters the second thimble which is curved reversely to the 90 first one and the other free end of the tip will be brought down so as to slightly overlap the first one. The rod passes on until it reaches the cutting knives which severs it in the middle of the tip. 95

In the figures forming part of this application Figure 1 is a perspective view of a cigarette machine with my improvements attached thereto. Fig. 2 is a front elevation thereof. Fig. 3 is a plan view. Fig. 4 is a 100 sectional view showing the application of the tip to the rod. Fig. 5 is an end elevation taken in a similar direction to Fig. 4. Fig. 6 is a sectional view through the knives and block as it first applies the cork tip to the 105 rod. Fig. 7 is a perspective view of the block. Fig. 8 is an elevation showing the ratchet arrangement by which the paste wheel is operated. Fig. 9 is a perspective view of a number of the parts shown in Fig. 110

6. Fig. 10 is an end elevation of the stirrup feeding device which feeds the cork strip to the machine. Figs. 11, 12, and 13, are perspective views of the thimbles which finally 5 secure the cork tip in place. Fig. 14 is an elevation showing the tip as it is applied. Figs. 15 and 16 are plan views showing the action of the tip as it passes through the thimbles, and Fig. 17 is an end elevation 10 showing the same action, the rod being shown in section. Fig. 18 is a side elevation of a forming mechanism of a cigarette machine. Fig. 19 is a plan view of Fig. 18, and Fig. 20 is a side elevation with parts broken away to 15 show the interior.

My improvements are adapted for use in a cigarette machine in which a cigarette rod is formed and then moved in the direction of its length, and for that reason I have illustrated 20 a conventional form of forming mechanism.

By referring to Figs. 18 to 20 inclusive, it will be seen that the forming mechanism consists of the following:—A wheel 97 is journaled 25 to a portion of the frame of the machine, and likewise a pulley 98 is journaled in alignment with the first pulley 97, and a continuous belt 99 engages over the two pulleys and is kept in proper tension by tension 30 pulleys 100 and 101. The belt 99 passes over plate 102 of the machine and is adapted to carry on its upper surface the strip of paper 103 from which the cigarette rod is to be made. A hopper 104 feeds the tobacco upon 35 the paper strip 103, as it is passing through a chamber 105, and the tobacco in passing under rollers 106 and 107 is properly distributed on the paper strip and the paper and tobacco are then passed through the 40 former which consists of folding plate 108 which brings the edges of the paper over so that they overlap, and means are applied through the apertured plate 109 which causes the adhesive that has been applied to 45 the paper to properly seam the rod as it is formed.

In Fig. 18 there is illustrated a pulley 110 which is also journaled to the frame of the machine. Belt 111 passes over this pulley 50 and engages with a series of smaller pulleys 112 to 117 inclusive, so that the belt will pass through the casing 118 toward the rod as it is formed and above which the belt engages for the purpose of moving the rod longitudinally. The continuous action of the belts 99 and 111 exert a continuous traveling motion 55 to the cigarette rod as it passes through the former, and after passing through the latter, the tip is applied by my improved mechanism; as will appear hereafter.

The tipping feature of the machine consists, primarily, of a bed 1, which in this case is a part of the cigarette machine. This bed 60 serves as a support for the various parts of the tipping machine on which the greater

portion of the same moves longitudinally. The movable parts of the tipping machine are supported upon, and are carried by bed plates 2 and 3, which are bolted together, and rest upon the plate 4, in such manner 70 that it will have a free longitudinal movement thereon. Extending vertically from a stationary plate 4 secured to the bed, are vertical supports 5 which support the hub 6, in which is journaled the shaft 7; this shaft 75 on its end carries a bevel gear 8 which meshes with another gear 9 on a vertical shaft 10. The latter is connected, as will be seen in Fig. 3, with the main driving shaft 11 of the cigarette machine, so that power is transmitted to the shaft 7 and to the vertical wheel 12, which is secured to the shaft 7 on the opposite side of the hub 6 to that of the gear. The wheel 12 carries on its front face 80 a pin 13 which travels in a certain arc, for the purposes which will appear hereafter. The horizontal block 14 is preferably secured to the hub 6 and support 5, by means of a bracket 15 which partly surrounds the wheel 12. This block is stationary and serves as a 85 guide for the movable parts of the machine. Extending upwardly from the bed plate 3 is a vertical support 16, which has laterally projecting arms 17 and also a plate 18 at the rear thereof which engages with the stationary block 14 by a miter connection 14^a so that the plate 18 may move longitudinally 90 of the direction of the entire machine and without having vertical movement thereon. There is also secured in the plate 18 by another miter connection 18^a, only vertically arranged, a cam block 19, which has vertical 95 movement with relation to plate 18, and is carried by it when it reciprocates longitudinally. A space is provided in the block 14 100 as shown in dotted lines in Fig. 3, so as to allow for the longitudinal movement of the cam block 19. This cam block 19 is provided with a groove 20 which is vertical, and which turns off at an angle 21. The purpose of this groove is to engage a pintle 22 105 which is secured to a lever 23 by a bolt 24 in a slot 25, which is fulcrumed on the bracket 17 by a pin 26, and extending forward at an angle from the lever 23 is a second lever 27 110 which moves with the latter, and is preferably made an integral part thereof, the two forming a bell crank. The latter has fulcrumed to its end, upwardly projecting arms 28 which carry the block 29 adapted for 115 primarily securing the cork tip to the cigarette rod.

The movement of the lever 23 is caused by the vertical action of the cam block 19 which transmits its action through the grooves 20 120 and 21 and pintle 22, and thus through the lever 27 and arms 28 to the block 29, so that the latter will move in a vertical direction, and for the purpose of guiding the block 29, I provide vertical extensions 30, which move 125

130

in a slot 31 in the bracket 32, the latter being supported by the support 16. From this same bracket 32, there extends a plate 33 having in its recess 34 a concave wheel 35, journaled upon the pin 36. This latter is so positioned that it will engage with the top of the cigarette rod and guide it as it passes through the tipping machine. Secured to the plate 33 is a knife 37, with its cutting edge downward, and on the block 29 is carried a second knife 38 opposite to knife 37, so arranged that their cutting edges will pass in close proximity and sever whatever is passed between them.

Extending upwardly from the base plate 2 is a vertical support 39, which supports the plate 40 for the purpose of feeding and cutting the cork strip 41. Plate 40 is provided with an aperture 42. There is also a vertical support 43 connected to and carried by the base plate 2 on which is journaled a roller 44, the latter engaging with the cork strip through the aperture 42 in the plate 40. There is also journaled on the support 43, a second roller 45, which is placed directly above the roller 44 so that it will engage the cork strip so as to form a close contact between the two rollers. The roller 45 is so formed on its periphery as to enable the paste to be applied to the cork strip, as well as acting as a guide for the strip. As will be seen in Fig. 1, the periphery of the roller is provided with two grooves 46 in which the arms 47 secured to the plate 33 engage for the purpose of holding the roller in proper lateral relation to the cork strip. The paste cup 48 is also supported by the vertical stand 43, and supplies paste to the roller 45.

The cork strip is fed on to the plate 40 by an automatic feeding and controlling mechanism, which is actuated through the medium of the block 19, so that the several movements are controlled from the same place and act in unison. This feeding mechanism, which is the same as in my former patent, is constructed as follows:— The bracket 49 extending outwardly from the frame, has an oscillating beam 50 pivoted thereto at the point 51, and also has an upwardly extending arm 52, which is provided with a swinging stirrup 53, and secured to the same pivotal point 51 is a movable plate 54. The stirrup 53 and the plate 54 having flat jaws 55 and 56, cause the strip 41 to be gripped between them because of the swinging of the stirrup on the pin 57 at a different arc from the plate 54. The beam 50 is oscillated on its pivot by means of the connection through the bolt 58 to the block 19, the slot 59 allowing for proper movement of the bolt 58, and causes the strip to be fed forwardly over the guide arm 60, and the roller 61 in the proper position on the plate 40. The opposite end of the beam 50 is secured by a slotted connec-

tion to the rod 62 by means of a bolt 63, which moves in a slot 64 and is in a curved position, so that its lower end is secured to a ratchet arrangement for actuating roller 45. This connection and its operation may be seen clearly in Fig. 8. The lower end of the rod 62 is provided with an arm 65 by means of a pin 66, which also moves in a slot 67, the arm 65 being fulcrumed on the axle of the roller 45. This arm 65 carries a pawl 68 which engages with a ratchet 69, also secured on the axle of the roller 45, so as to move therewith. The spring 70 engages with the pawl 68 so as to keep it in contact with ratchet 69. As will be seen in this figure, the normal position of the pawl is about one-half along the length of one of the teeth of the ratchet, for the purpose which will appear hereafter. At each movement of the beam 50, the rod 62 serves to rotate the roller 45, so as to transmit the paste upon the strip and also feed the strip. As will be seen in Fig. 1, there is placed between the movable pasting machine and the cutting knife, a pair of curved thimbles, the shape of which will be more apparent in Figs. 11 to 17 inclusive. The first one 70 is so disposed upon the base 1, by means of a bracket 71, as to be in proper alignment with the cigarette rod. As the rod passes through this first thimble, the various tips which have been partially applied to the rod, will be partially folded upon the rod and will then pass into the second thimble 72, which is also secured by a bracket 73, and is disposed in a reverse position to that of the first thimble. Beyond this is a revolving knife 74, turning upon its shaft 75 and operated by a belt 76. Details of this cutting device, I do not claim, *per se*, in this case, for the reason that it does not form a part of my invention, except with relation to the other parts.

The operation of my machine is as follows: The revolutions of the wheel 12 exert through the pin 13, the vertical movement upon the cam block 19, the latter being adapted to respond only to the vertical movement, and the bed plates travel on the bed in a horizontal direction, which is permitted by the blocks 14 and 18, so that the machine moves bodily longitudinally, and the cam block 19 moves vertically, and transmits motion through the beam 50 to the feeding mechanism carried above it, and also moves the rod 62, and causes the roller 45 to rotate a portion of one revolution through the pawl and ratchet action, so that the strip 41 will be fed from above by the stirrup action, and also carried along below between the two rollers 44 and 45, so that the end of the cork tip will be fed across the top of the block 29, sufficient to form a tip of proper dimensions to surround the cigarette rod and allow for overlapping. When this

feeding is taking place, the pintle 22 is traveling in the vertical groove 20, and as the feeding ceases, it then is directed by a slanting groove 21, so that the lever 23 is thrown back upon its fulcrum, thus causing the lever 27 to rise carrying with it block 29, when the same will engage with the portion of the strip which projects over it and bring it in partial contact with the cigarette rod 90; in doing so, the groove 92 in the block 29 causes the tip to partially surround the cigarette rod so that it is sufficiently adhered to it; while this action is taking place, knives 37 and 38 are severing 10 the end of the cork tip; while this action is taking place, the concave roller 35 guides the cigarette rod and supports it at the opposite side to the block 29. While this action is taking place, the tipping machine 15 has been traveling substantially the length of two cigarettes; the tip is now partially applied and the tipping machine returns to its former position ready for a further application.

25 As explained heretofore, the pawl 68 does not lie right against one of the teeth of the ratchet in its normal position; the reason for this is that the operating levers should first cause the knives to sever the end of the strip 30 before the pawl acts upon the ratchet so that the roller 45 will not commence to feed a new portion of the strip until the first piece has been disposed of, as otherwise it would have the tendency to crowd the strip against the knives. When this part of the mechanism 35 has ceased its work, the rod passes on; as is shown in Fig. 1, and enters the first folding thimble; as it enters this thimble 70, it first meets the projecting end 93, when the spiral 40 94 will exert a curling tendency upon the right free end of the tip until it passes to the rear end of the thimble. At that time the end of the tip is brought down securely upon the cigarette rod and the adhesive will cause 45 it to become secure; it then passes on to the second thimble 72, which is similar to the first one, except that it is curved in the reverse direction. It first meets the projecting end 94, and the remaining free end of the 50 tip will be folded over by the spiral edge 95, until by the time it reaches the end of the thimble, the tip will be entirely secured to the cigarette rod. As the tip is slightly larger than the circumference of the rod, the 55 ends will be partially overlapped. From this the rod passes on to the guide 87, when the knife 74 will come down and sever the rod in exactly the center of the tip; after this the knife will return and sever the rod at a 60 point intermediate of the tip, because the cigarettes are made in alternate positions, in other words, the knife cuts twice while the tipper is putting on one tip for two cigarettes. The strip is fed from a suitable roller 65 88 which is provided on a support 89.

Having described my invention, what I claim is:

1. In a cigarette machine, means for forming a cigarette rod and moving the same in the direction of its length and means interposed in the path of the cigarette rod for applying cork tips to the cigarette rod, after it comes from the "former".
  2. In a cigarette machine, means for forming a cigarette rod and moving it in the direction of its length and means operating transversely of the cigarette rod for applying tips thereto after the rod comes from the "former".
  3. In a cigarette machine, means for forming a cigarette rod and moving it in the direction of its length and means interposed in the path of the cigarette rod, traveling in the direction thereof, and adapted to apply tips to the rod while traveling with it.
  4. In a cigarette machine, means for forming a cigarette rod and moving it in the direction of its length and means traveling in the direction of the cigarette rod and adapted to transversely apply a tip thereto while traveling with the rod.
  5. In a cigarette machine, means for forming a cigarette rod and moving it in the direction of its length and means for partially attaching a tip to the cigarette rod, and means through which the rod passes, for completing the attachment of the tip to the rod.
  6. In a cigarette machine, means for forming a cigarette rod and moving it in the direction of its length and reciprocating means adapted to travel in the direction of the cigarette rod and adapted to attach a tip to the rod while traveling in the direction of the rod.
  7. In a cigarette machine, means for forming a cigarette rod and moving it in the direction of its length and means for feeding a tipping strip transversely of the cigarette rod, means for attaching the strip transversely on the rod and means for cutting the strips.
  8. In a cigarette machine, means for forming a cigarette rod and moving it in the direction of its length and means for feeding a strip across the path of the cigarette rod, means for bringing the strips in contact with the rod and means moving simultaneous with the last means, for severing the tipping strips, and means for completing the application of the tip to the rod.
  9. In a cigarette machine, means for forming a cigarette rod and moving it in the direction of its length and means for feeding a strip across the path of the cigarette rod, a grooved block for causing the strip to contact with the cigarette rod, means for severing a tip from its strip and means for securing the ends of the tip on the rod.
  10. In a cigarette machine, means for form-
- 80

ing a cigarette rod and moving it in the direction of its length and means for feeding a strip across the path of the cigarette rod, means for causing a tip to contact with the rod, said last means moving in the direction of the rod while acting on the tip, and means interposed in the path of the rod for securing the ends of the tips to the rod. 5

11. In a cigarette machine, means for forming a cigarette rod and moving it in the direction of its length and means interposed in the path of the cigarette rod, for feeding a cork web and means for severing and securing the cork web to the cigarette rod at intervals. 10

15. 12. In a cigarette machine, means for forming a cigarette rod and moving it in the direction of its length and means interposed in the path of the cigarette rod and adapted to feed a cork web intermittently, means for severing 20 the cork web and means for securing the cork tip to the cigarette rod.

25. 13. In a cigarette machine, means for forming a cigarette rod and moving it in the direction of its length and means for feeding a cork web to the cigarette rod, means for applying paste to the said web, and means for severing the web and securing the tip to the cigarette rod.

30. 14. In a cigarette machine, means for forming a cigarette rod and moving it in the direction of its length and means for feeding a web to the cigarette rod, a roller adapted to apply paste thereto, and means for severing the web and applying the tip to the cigarette rod.

35. 15. In a cigarette machine, means for forming a cigarette rod and moving it in the direction of its length and means for feeding a strip to the cigarette rod, a grooved block under the cigarette rod for causing the strip 40 to contact with the cigarette rod, a concave roller above the cigarette rod, and means for severing a tip from the strip and securing it to the rod.

45. 16. In a cigarette machine, means for form-

ing a cigarette rod and moving it in the direction of its length and means for feeding a strip to the cigarette rod, means for severing the strip and applying the tip to the rod, and means interposed in the path of the rod for securing the free ends of the tips to the rod. 50

17. In a cigarette machine, means for forming a cigarette rod and moving it in the direction of its length and means for feeding a strip to the cigarette rod, means for severing the strip and applying the tip to the rod, and means interposed in the path of the rod for securing the free ends of the tip to the rod so that they overlap. 55

18. In a cigarette machine, means for forming a cigarette rod and moving it in the direction of its length and means for applying a tip to the cigarette rod and means for securing the free ends of the tip to the rod comprising spirally disposed members through which the cigarette rod passes. 60

19. In a cigarette machine, means for forming a cigarette rod and moving it in the direction of its length and means for applying a tip to the cigarette rod and means for securing the free ends of the tip to the rod comprising 70 members having reversely curved spirals which are adapted to bring the ends of the tip in contact with the rod.

20. In a cigarette machine, means for forming a cigarette rod and moving it in the direction of its length and means for feeding a strip to the cigarette rod, a block adapted to bring the strip in contact with the rod, means for severing the strip, and means for securing the free ends of the tip to the rod comprising 75 a plurality of reversely curved spiral thimbles through which the rod passes. 80

Signed this 9th day of October 1906.

ARTHUR L. BOUCHER.
